assignor to Shellmar Products Corporation,
Mount Vernon, Ohio, a corporation of Delaware

Application February 2, 1946, Serial No. 645,079

5 Claims. (Cl. 93—6)

1

This invention relates to improvements in bags and methods of filling the same, having particular reference to a multi-wall bag structure in which an inner liner bag is partially inserted within an outer reinforcing bag to the end that the inner liner bag readily can be filled, sealed and dropped to the bottom of the outer bag, whereupon the outer bag can then be secured together, preferably free of the inner bag, and the provision of such a bag structure and method of filling and closing the same is a principal object of the invention.

Conventional multi-wall bags made of paper, cloth or composite materials are not moisture-proof or airtight to any appreciable extent. This is due in part to perforations in the bag structures occurring during the stitching or sewing operations in providing the bottom and top closures. Such bags are also provided with overlapped vertical back seams which are glued together. Corrosive or chemically active ingredients packed in such bags will attack the glue in the seam from the inside of the bags and break down the seam constructions. Such bags when filled lack proper and desirable hermetically sealed characteristics. Furthermore, such bags are not lined or coated to impart grease-proof properties thereto.

Generally, it is another object of the invention to overcome the foregoing difficulties and other disadvantages by providing such a bag with an insertable inner liner bag whereby the composite structure readily can be filled and sealed for shipping.

More specifically, it is an object of the invention to provide a multi-wall bag structure and method of filling the same in which an outer reinforcing bag is utilized having an inner liner bag with an inner area equal at least to the inner area of the outer bag, with the inner bag inserted within the outer bag so that its bottom is spaced from the bottom of the outer bag a substantial distance with the top of the inner bag extending from the top of the outer bag, whereby the bottom of the outer bag can be squeezed together below the bottom of the inner bag, the inner bag filled and sealed so that it can be dropped to the bottom of the outer bag and the latter closed and secured together across the top.

Other objects of the invention will in part be obvious and will in part appear hereinafter.

The invention accordingly comprises the several steps and the relation of one or more of such steps with respect to each of the others, and

2

the article possessing the features, properties, and the relation of elements, which are exemplified in the following detailed disclosure, and the scope of the application of which will be indicated in the claims.

For a fuller understanding of the nature and objects of the invention reference should be had to the following detailed description taken in connection with the accompanying drawings, in

10 which:

Fig. 1 is a view illustrating an outer reinforcing bag;

Fig. 2 illustrates an inner liner bag for said outer bag;

Fig. 3 illustrates the inner liner bag partially inserted within the outer bag;

Fig. 4 is a view of an inner liner bag as it appears when inserted in a gusseted outer reinforcing bag;

Fig. 5 is a sectional view illustrating the composite bag structure set up for filling;

Fig. 6 is a sectional view illustrating the composite bag structure being filled;

Fig. 7 is a view, partly in section, illustrating the sealing of the inner bag structure after filling;

Fig. 8 is a sectional view illustrating the inner liner bag being permitted to settle to the bottom of the outer reinforcing bag;

Fig. 9 is a view, partly in section, illustrating the closing of the outer bag over the inner liner bag;

Fig. 10 is a side view of the filled and closed bag of Fig. 9; and

Fig. 11 is a view, partly in section, similar to that illustrated in Fig. 9 showing the sealed inner liner bag joined together at its seam structure with the seam structure of the outer reinforcing bag.

Referring more particularly to the drawings there is indicated generally at 10 a multi-wall bag of the type, for example, used for packaging granular materials. Because of the weight of such commodities it is necessary that these bags be very strong and it is customary to make them in a plurality of layers 11 to provide the necessary strength characteristics. An overlapped and glued seam construction is provided at 12. Such bags are conventionally sewn or stitched

50 across the bottom as indicated at 13. After such a bag has been filled it is stitched across the top.

A bag of the foregoing type has great strength but because of the stitching in the seam area a suitable siftproof, moisture-vaporproof construc-

tion cannot be provided. Also, because of the overlapped vertical seam 12 there is a tendency for the bag to leak because the seam tends to break down when chemical or corrosive materials are packed in the bag.

In accordance with the principles of the present invention it is possible to utilize such a bag, or similar bag which will function as an outer reinforcing structure, by the insertion therein of an inner liner of the type indicated generally at 15, Fig. 2. Such a liner may comprise any suitable fibrous or non-fibrous material which heat-sealable characteristics. For example, such material as pliofilm could be used or sufficiently heavy heat-sealing cellophane. The liner bag may be of paper material having an overall or marginal application of a heat-sealable material. If no heat-sealable material is used and the bag is made by marginal applications of any other suitable adhesive, the closure can be effected by a similar adhesive.

The inner liner bag 15 can be made from a single web of such materials folded transversely to provide a bottom closure as indicated at 16. The structure is then sealed marginally as at 17 to provide side wall seams.

Another method of making such a bag is to superpose two webs of such material and marginally heat-seal the bottom and opposite sides.

A further type of bag which can be utilized in connection with the present invention is to completely seal the bag, leaving a valve opening, or providing such an opening by cutting away a portion of the bag whereupon the same can, after filling, be heat-sealed together. Such a bag structure is more fully described and claimed in my copending application Serial No. 627,643, filed November 9, 1945.

In any event, where it is desired to provide a moisture-vaporproof inner liner and one which will be greaseproof a web of material should be used which inherently has such characteristics; or a web should be used which has an overall coating of a suitable surfacing agent whereby such characteristics, including heat-sealable properties, will be provided.

It is an important feature of the invention that the inner surface area of the inner liner bag be at least equal to the area of the inner surface of the outer wall bag. In fact, it is preferable to have the inner wall bag somewhat oversize as compared with the outer wall bag as illustrated in Figs. 1-4 of the drawings.

The inner liner bag should be partially inserted within the outer reinforcing bag so that the bottom of the inner bag is spaced a substantial distance from the bottom of the outer wall bag as depicted in Fig. 3. This will permit the inner wall bag 15 to extend approximately an equal distance beyond the top of the outer wall bag.

Preferably, the marginal vertical seams 17, together with as much of the adjacent inner liner as is necessary, may be folded over as illustrated in Fig. 4 to insert the same within the outer reinforcing bag. In this figure the outer reinforcing bag is illustrated as being of the gusset type. It should be understood that the invention is intended to apply to pouch types or gusseted types of bag and this includes both the inner liner bag as well as the outer reinforcing bag.

The composite structure of the inner liner bag partially inserted in the outer reinforcing bag may be shipped in this condition. Because of the snug fit of the inner liner bag within the outer reinforcing bag the former will not easily tend to

settle to the bottom of the outer bag or become separated therefrom. When such bags are separated from a stack they are quickly available for handling in connection with filling and sealing operations.

When an operator desires to fill such a bag he may pinch the outer wall bag together at the bottom just below the inner wall structure as more or less diagrammatically illustrated in Fig. 5. A guide mark on the outer bag can be utilized to indicate the position of the bottom of the inner bag. Suitable adjustable clamp members 18 may be utilized for this purpose. These may be placed on a movable structure which can be transported to a filling spout. The clamping members may be operated manually, by a foot treadle, or automatically.

As soon as the mounted composite bag structure has been moved under a filling spout 19 the bag may be filled as illustrated in Fig. 6. The weight of the material will tend to bulge the walls of both bags outwardly. As soon as the bag has been filled the inner bag will be accessible for the sealing operation.

In sealing it is easy to bring the opposite faces of the mouth opening of the bag together and secure them in position depending upon the type of liner construction used. That is, the mouth opening may be adhesively sealed together where a heat-sealable material has not been utilized in providing the liner construction. If the liner has inherent heat-sealing characteristics, or is provided with a material which is heat-sealable, it is but necessary to apply heat and pressure to the mouth opening by means of conventional sealing irons 20 (Fig. 7).

It will be appreciated that the operator has not found it necessary to reach down within the outer bag to perform the sealing operation. Because of the fact that the inner liner bag projects a considerable distance above the reinforcing bag, the closing operation is comparatively simple because of the accessibility of the mouth closure of the inner bag for sealing purposes.

As soon as the inner bag has been filled and sealed the clamping members 18 can be moved apart a sufficient distance to permit the inner bag to settle to the bottom of the outer bag. This can be done by holding the sides of the outer bag either by mechanical or manual means.

As soon as the bag has settled into the position illustrated in Fig. 8 the sealed portion of the inner liner indicated generally at 21, preferably is folded over as indicated at 22 in Fig. 9. The outer bag can then be brought together and secured by means of stitching as indicated at 23.

In the modification shown in Fig. 11 the inner liner bag 115 is secured to the outer reinforcing bag 118. This may be done by inserting the sealed portion of the inner liner between the opposed faces forming the opening of the outer wall bag and stitching both together as indicated generally at 123. Care should be taken that the stitching enters through the sealed portion of the inner bag so that there is no penetration in the throat area.

In the preferred embodiment the closure of the inner liner bag is folded down into the outer reinforcing bag so that the inner liner bag is completely free from any attachment to the outer bag. The fact that the inner liner bag is at least of the same inner surface area as the inner surface area of the outer wall bag, or preferably somewhat oversize, will prevent pressure exerted

by the weight of materials from rupturing the inner liner bag.

It will thus be seen that the objects hereinbefore set forth may readily and efficiently be attained and since certain changes in carrying out the above method, and certain modifications in the article which embody the invention may be made without departing from its scope, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A method of filling composite bag structures of the kind described which comprises providing an outer reinforcing bag and an inner liner bag of at least equal inner area to said outer bag, inserting said inner bag within said outer bag so that its bottom is spaced from said outer bag a substantial distance with the top of said inner bag extending from the top of said outer bag, squeezing together the bottom of said outer bag below the bottom of said inner bag, filling said inner bag, closing and securing together the top portions thereof, permitting the inner bag to settle to the bottom of the outer bag, and closing and securing together the top portions of the outer bag above the inner bag.

2. A method of filling bags of the kind described which comprises providing an outer reinforcing bag and an inner liner bag of at least equal inner area to said outer bag, inserting said inner bag within said outer bag so that its bottom is spaced from said outer bag a substantial distance with the top of said inner bag extending from the top of said outer bag, squeezing together the bottom of said outer bag below the bottom of said inner bag, filling said inner bag, adhesively sealing together top marginal wall portions thereof, permitting the inner bag to settle to the bottom of the outer bag, and closing and securing together the top of the outer bag above the inner bag.

3. A method of filling bags which comprises providing an outer reinforcing bag and an inner liner bag of heat-sealable material and of at least equal inner area to said outer bag, inserting said inner bag within said outer bag so that its bot-

tom is spaced from said outer bag a substantial distance with the top of said inner bag extending from the top of said outer bag, squeezing together the bottom of said outer bag below the bottom of said inner bag, filling said inner bag, heat-sealing together top marginal wall portions thereof, permitting the bottom of the inner bag to settle to the bottom of the outer bag, and closing and securing together the top of the outer bag above the inner bag.

4. A method of filling bags which comprises providing an outer reinforcing bag and an inner liner bag of heat-sealable material and of at least equal inner area to said outer bag, inserting said inner bag within said outer bag so that its bottom is spaced from said outer bag a substantial distance with the top of said inner bag extending from the top of said outer bag, squeezing together the bottom of said outer bag below the bottom of said inner bag, filling said inner bag, heat-sealing together top marginal wall portions thereof, permitting the inner bag to settle to the bottom of the outer bag, and stitching together top marginal wall portions of the outer bag with said marginal wall portions of said inner bag secured between the stitched top marginal wall portions of said outer bag.

5. A method of filling composite bag structures of the kind described which comprises providing an outer reinforcing bag and an inner liner bag of at least equal inner area to said outer bag, inserting said inner bag within said outer bag so that its bottom is spaced from said outer bag a substantial distance with the top of said inner bag extending from the top of said outer bag, squeezing together the bottom of said outer bag below the bottom of said inner bag, filling said inner bag, closing and securing together the top portions thereof, permitting the inner bag to settle to the bottom of the outer bag, and closing and securing together the top portions of the outer bag.
